UNITED STATES PATENT OFFICE.

GEORGE N. ANDRICOPOULOS, OF SPRINGFIELD, MASSACHUSETTS.

SHIP-PROTECTOR.

1,241,602.

Specification of Letters Patent.

Patented Oct. 2, 1917.

Application filed November 22, 1916. Serial No. 132,887.

To all whom it may concern:

Be it known that I, GEORGE N. ANDRICOPOULOS, a subject of Greece, residing at Springfield, in the county of Hampden, 5 State of Massachusetts, have invented certain new and useful Improvements in Ship-Protectors; and I do hereby declare the following to be a full, clear, and exact description of the invention, such as will enable 10 others skilled in the art to which it appertains to make and use the same.

This invention relates to improvements in ship protectors and particularly to devices for protecting ships from injury from tor- 15 pedoes, mines, icebergs, rocks, and other like objects which would cause the formation of holes in the hull of the ships and the sinking thereof.

One object of the present invention is to 20 provide a device of this character which is arranged to be secured to the sides of a ship below the water line and which is disposed a suitably spaced distance from the sides of the hull to cause the explosion of a 25 torpedo far enough away from the ship to prevent any injury to the ship.

Another object is to provide a device of 30 this character which can be quickly and easily raised to lie in inoperative position against the sides of the ship, at times, and lowered to a point below the water line to 35 fully protect the sides of the ship at times.

Another object of the present invention is to 35 provide a device of this character which can be applied to any of the war ships or merchant ships now in use without any modifications of the ships.

Other objects and advantages will be apparent from the following description when 40 taken in connection with the accompanying drawings.

In the drawings:

Figure 1 is an elevation of a side elevation of a ship's hull showing my invention ap- 45 plied thereto and in lowered or operative position.

Fig. 2 is a top plan view of one side of the ship's hull showing the device in the position of Fig. 1.

50 Fig. 3 is an enlarged vertical sectional view taken on the line 3—3 of Fig. 1.

Fig. 4 is an enlarged horizontal sectional view taken on the line 4—4 of Fig. 1.

55 Fig. 5 is an enlarged top plan view of one of the suspending arms and fragments of the armor plates connected therewith.

Fig. 6 is an enlarged side elevation of the parts shown in Fig. 5, partly in section.

It is well known that the injury to a ship's hull by a torpedo is due to the fact that the 60 explosion of the torpedo takes place against the side of the hull. If the torpedo could be made to explode a few feet from the side of the hull the danger of an opening being blown in the hull would be reduced to a 65 minimum. It is the particular object of the present invention to provide a device which will receive the impact of the torpedo and cause the explosion of the same at such a distance from the side of the ship that the 70 latter will not be injured.

The same is true when the ship strikes an iceberg, a submerged reef or rock, or other hard submerged object. With a protector which is spaced from the sides of the ship's 75 hull a sufficient distance to receive the impact, the hull will be effectively protected from injury.

The above objects are attained by means of the device illustrated in the accompanying drawings, in which the preferred embodiment of the invention is shown.

Referring particularly to the accompanying drawings, 10 represents the hull of a ship in connection with which my invention 85 is used. Mounted on the deck or other suitable point adjacent the side of the ship, is a shaft 11 which extends the length of the ship. On this shaft are secured a number of grooved wheels 12, to which are secured one end of a series of chains 13. The shaft is suitably supported in the bearing brackets 14. At the front and at the rear of the ship are the shorter shafts 15, which are connected to the adjacent ends of the shaft 11 90 by the universal joints 16. One end of one of the short shafts is suitably connected to an engine or motor of suitable design for 95 rotating the shafts.

On the sides of the hull, approximately 100 coincident with or slightly above the water line, are secured a plurality of brackets 17, and pivotally mounted on these brackets are the arms 18. On the outer end of each of these arms there is secured an angle member 19. There are three or more horizontal rows of brackets 17 and attached arms 18, and secured to the said angle members by their vertical edges are the protective armor plates 20, said plates being arranged in overlapping relation but spaced apart, as clearly 110 seen in the sectional views. Secured to each

of the plates by the same means which secure the plates to the angle members, are the channel members 21, and secured to the outer portions of the channel members are 5 the other vertical edges of the armor plates. Thus the plates stand in vertical planes but inclined outwardly and rearwardly from the sides of the ship. The before-mentioned chains are secured to rings 22 carried by the 10 upper ends of certain of the uppermost of the armor plates.

It will be noted that the general contour of the whole armored section is in conformity with the outline of the hull of the ship, 15 and is arranged in spaced parallel relation to the sides thereof.

As seen in Fig. 4, the armored section is raised into inoperative position. In this position the plates lie close to the sides of 20 the hull and thus do not in any way impede the progress of the ship. When in the position of Fig. 3 the arms are in full lowered position and the armor plates in proper spaced distance from the sides of the ship. 25 These plates, when in lowered position, are disposed a distance of several feet from the ship's side, and when a torpedo strikes the armored section the torpedo will explode at that distance from the ship, thus effectively 30 protecting the ship from injury.

It will be noted that each of the brackets 17 is formed with a shoulder 23 on which the arm 18 rests so as to be supported in a horizontal position from the side of the ship.

Copies of this patent may be obtained for five cents each, by addressing the "Commissioner of Patents Washington, D. C."

It will also be noted that the armored sections are disposed below or at the water line of the ship, that is the upper edges of the plates are disposed above the water line, while the greater portion of the armor is disposed below the line and extends as low 40 as the ship's keel, or close thereto. The whole force of the explosion of a mine or torpedo or the impact of a rock or iceberg will be sustained by the armored sections of the device, thus preventing contact of the 45 submerged object with the hull of the ship.

By means of the shaft and the connecting chains, the sections can be quickly and easily lowered or raised as desired, the sections being lowered when the ship approaches a 50 danger zone, and raised when the zone has been passed.

What is claimed is:

A protection device for a ship comprising 55 armored sections each consisting of a plurality of vertical plates inclining outwardly and rearwardly from the ship, angle members between and securing the plates together, and pivoted arms carried by the ship and pivotally connected to the sections, 60 whereby said sections are capable of being raised and lowered.

In testimony whereof, I affix my signature, in the presence of two witnesses.

GEORGE N. ANDRICOPOULOS.
